UNITED STATES PATENT OFFICE.

HORACE B. SHATTUCK, OF LOWELL, MASSACHUSETTS.

SHUTTER-FASTENER.

SPECIFICATION forming part of Letters Patent No. 242,381, dated May 31, 1881.

Application filed March 16, 1881. (No model.)

To all whom it may concern:

Be it known that I, HORACE B. SHATTUCK, of the city of Lowell, county of Middlesex, and State of Massachusetts, have invented a new 5 and useful Improvement in Window-Blind Fastenings, of which the following is a specification.

My improvement relates to spring-fastenings for blinds or shutters, made of wire; and 10 its objects are to provide a wire spring-fastening which shall be supported upon an unyielding bearing to make a quick-acting spring, and to prevent its becoming indented into the wood of the blind to which it is attached, and at the 15 same time to support it transversely, to permit of a greater proportion of the entire length of the wire forming the fastening being used for the spring-arm than has been heretofore done, and to provide a fastening-spring little liable 20 to get out of order. I attain these objects by the mechanism illustrated in the accompanying drawings, in which—

Figure 1 is an elevation showing my device attached to a window-blind in position. Fig. 25 2 is an elevation of the fulerum or bridge seen in Fig. 1. Fig. 3 is a plan view of the spring, showing the eye and loop, not seen in Fig. 1.

A is the building to which the blind B is attached. 30 C is a wire spring designed to engage with a catch, D, placed upon the sill of the window when the blind is closed, and a somewhat similar catch placed upon the side of the house when the blind is open. These catches are inclined upon their outer and upper sides, and provided with a notch at the upper end of the incline, and so placed upon the side of the building and upon the window-sill that the spring-fastener will, as the blind is swung toward the one or the other, come into contact with the inclined side, and be sprung as it slides upward toward the notch, reaching which the wire spring drops into it and holds the blind. The spring-fastener is attached to the 40 under edge of the lower cross-bar of the blind by a screw, e, which passes through an eye, e², formed by bending the end of the wire forming the spring-fastener. The wire forming the spring is bent so as to have a short inclined 45 brace-arm, c, reaching obliquely away from the eye through which the screw e passes, and

when thus raised from the surface of the wood it is continued parallel with it, forming the spring-arm c², whose extremity is bent into a loop or ring, which can be readily taken hold 55 of to unfasten the spring from the catches.

Under the spring, at the point where the long and short arms unite, is placed the fulerum f, which has a hollow, f¹, formed upon its crown to receive the wire, a tang, f², to drive into 60 the wood to hold it in place, and shoulders f³ to prevent its sinking farther into the wood than it is at first placed.

g is a staple placed over the spring-arm of the fastener, near its end, to hold it from vibrating when not engaged with the catches upon the building, and to prevent its being bent sidewise beyond its limit of resilience when brought into contact with any object bearing 65 transversely against it.

Heretofore wire blind-fasteners have been made with a portion of the wire next to the point of attachment to the shutter lying parallel with and upon the surface of the wood to which they are attached, to give support to the 70 spring-arm comprising a continuation of the wire elevated above such surface. Such part which supported the spring-arm it has been found necessary to make of a considerable length, because otherwise it became embedded 75 in the wood, and the end of the spring-arm was not then maintained with resilient force sufficient to make an active and efficient spring. Another way of obtaining a greater elasticity, and providing for the depression of the supporting-point of the wire in contact with the wood into it, which is very likely to occur when the wood is wet, or to result from wear after the spring has been some time in use, is by forming a loop in the wire, to act as a fulerum 80 and come into contact with the wood, as shown in Patent No. 166,819; but all these methods require, to form an effective and durable spring, that the part of the wire coming in contact with the wood and forming the support for the 85 spring-arm bear at a considerable distance from the point of attachment; but the lengthening of the supporting part or the arm between it and the point of fastening, or the forming of a wire-loop support, must be effected 90 either by increasing the length of the entire device or the wire used in its construction, or 95 100

at the expense of the length of the spring-arm, the one method adding to the cost and the other reducing the elasticity and quickness of action of the spring and increasing the liability 5 to become "set" by being bent beyond the limit of its resiliency. Besides this, all springs which bear upon the timber at their fulcrum-points are less quick to act as that timber bearing yields with the pressure applied than when 10 they are supported upon a fulcrum which is unyielding.

I provide a metal fulcrum having sufficient hold and bearing upon the wood to always remain where placed, and, by reason of its incompressible nature, I can maintain a support 15 always unyielding, regardless of the condition of the wood into which it is placed, and therefore that can be placed very close to the point of attachment of the fastener, and the shorter 20 arm from the point of support to such point of attachment may be made of the least possible length without impairing the permanence of the structure; and therefore, without increasing the length of the fastener or the wire re-

quired to form the fastener, the spring-arm 25 may be made longer, because of such better support; and a greater quickness of action be obtained in the spring-arm also.

By providing the fulcrum with a tang which is driven a considerable distance into the wood, 30 and a hollow in the crown into which the wire is seated, a side support is given to the spring-arm, and it is prevented from pushing or crowding over and coming into contact with the staple placed over it near its extreme end. 35

What I claim is—

A spring-wire fastener having a fastening-eye, e^2 , inclined brace-arm e , and horizontal spring-arm e' , in combination with the fulcrum f , provided with the tang f^2 , and shoulders f^3 , 40 extending each way from the tang transversely to the line of direction of the spring-arm, substantially as described.

HORACE B. SHATTUCK.
